CLAIM

The ornamental design for a safety seat with anchor, as
shown and described.

DESCRIPTION

FIG. 1 is a front, right, and top perspective view of the safety
seat with anchor showing our new design;

FIG. 2 is a front, left, and top perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken (dashed) lines in the drawings show portions of
the safety seat with anchor that form no part of the claimed
design.

1 Claim, 8 Drawing Sheets
